(57) **CLAIM**

I claim the ornamental design for a leash for an electronic device, as shown and described.

DESCRIPTION

FIG. 1 is an elevation view of the left side of the leash for an electronic device;

FIG. 2 is an elevation view of the front of the leash for an electronic device;

FIG. 3 is a plan view of the bottom of the leash for an electronic device;

FIG. 4 is a plan view of the top of the leash for an electronic device;

FIG. 5 is an elevation view of the right side of the leash for an electronic device;

FIG. 6 is an elevation view of the rear of the leash for an electronic device;

FIG. 7 is an isometric view, from the back right, of the leash for an electronic device; and,

FIG. 8 is an isometric view, from the front left, of the leash for an electronic device.
